UNITED STATES PATENT OFFICE.

LEROY K. ROBBINS, OF ST. LOUIS, MISSOURI.

WELL-DRILLING MACHINE.

No. 834,642.

Specification of Letters Patent.

Patented Oct. 30, 1906.

Application filed January 25, 1906. Serial No. 297,798.

To all whom it may concern:

Be it known that I, LEROY K. ROBBINS, a citizen of the United States, residing in the city of St. Louis, in the State of Missouri, have invented certain new and useful Improvements in Well-Drilling Machines, of which the following is a full, clear, and exact description, reference being had to the accompanying drawings, forming part of this specification.

My invention relates to a machine for drilling wells or other holes in the earth; and the invention has for its object to provide a tilting samson-post which is rockingly supported on the carriage of the machine and in turn rockingly supports the walking-beam, whereby the walking-beam may be shifted to provide clearance for the tool-rope in withdrawing the tool from the well.

The invention further has for its object to so mount the temper-screw at the forward end of the walking-beam as to secure as nearly as possible a direct vertical movement of the temper-screw in order that the tool-rope may be raised and lowered in the hole being drilled in as nearly a vertical line as may be possible where a plain walking-beam is used.

Figure I is a view, partly in elevation and partly in vertical longitudinal section, of my machine. Fig. II is an enlarged elevation of the lower end of the tilting samson-post and its bearing. Fig. III is an enlarged view, partly in vertical section and partly in elevation, of the jack-rod and shift-rod that control the samson-post and the slide and box with which these parts are associated. Fig. IV is an enlarged view, partly in elevation and partly in vertical section, of the walking-beam and the upper end of the temper-screw connected thereto. Fig. V is an end view of the parts shown in Fig. IV.

1 designates one of the ground-wheels of the carriage of my machine, in which is mounted the axle 2. (See Fig. I.)

3 is a bolster surmounting the axle 2 and which supports the carriage-sills 4, that at their opposite ends are supported by suitable ground-wheels and axle.

5 designates a socket-box mounted upon the bolster 3 centrally of its ends. This box is provided with upwardly-extending ears, in which is mounted a pivot-rod 6, that is preferably held from rotation by one or more set-screws 7. (See Figs. I and II.)

8 designates a tilting samson-post which is

seated upon a rocking bed-block 9, that is positioned within the socket-box 5 and is provided with ears 10, through which the pivot-rod 6 passes, the ears 10 being preferably of such dimensions that they will rest upon the top surface of the socket-box for rocking motion thereon, thereby relieving the pivot-rod 6 from strain and from shearing action of the rocking-block ears thereon.

11 designates the walking-beam, which is rockingly connected to the upper end of the samson-post by brackets 12 and boxes 13, so that said beam may rock vertically relative to the samson-post.

Extending transversely of the carriage-sills 4 is a cross-bar 14, and mounted upon this cross-bar is a guide-box 15, that is provided with a longitudinal slot 16, the guide-box being located in alinement with the samson-post.

17 is a slide-block loosely fitted in the guide-box 15 and adapted to reciprocate in rearward and forward directions therein.

18 is a jack-rod having its upper end pivoted at 19 to the samson-post 8 and its lower end provided with a fork 20, that straddles the guide-box 15 and is loosely connected to the slide-block 17 by a pivot-pin 21.

22 is a throw-rod provided at its rear end with a fork 23, that straddles the guide-box 15 and is fitted to the pivot-pin 21 to connect the throw-rod to the slide-block. This throw-rod is horizontally positioned and extends forwardly from the guide-box 15 and through the socket-box 5. The forward end of the throw-rod rests upon a catch-plate 24, that is supported by the carriage-sills. The throw-rod is provided with a handle 25, projecting upwardly from its forward end, and it bears at its lower side a pin 26, (see Fig. I,) that is adapted to enter a pin-hole in the catch-plate 24. When the samson-post is to be tilted backwardly from the position seen in full lines, Fig. I, to the position seen in dotted lines, thereby throwing the walking-beam to clear the tool-rope, the handle 25 of the throw-rod 22 is elevated to withdraw the pin 26 from the pin-hole in the catch-plate 24.

The throw-rod is then shifted longitudinally in a rearward direction, thereby reciprocating the slide-block 17 in the box 15. When this movement takes place, the jack-rod 18 is carried rearwardly with the slide-block and the samson-post is tilted backwardly to the desired degree to move the forward end of the walking-beam out of the path of travel of

the tool-rope when the drilling-tool is being hoisted.

27 designates the temper-screw, that is of common construction and is equipped with a clamp 28, by which the tool-rope 29 is gripped.

The forward end of the walking-beam 11 has therein a vertical notch 11', and secured to this end of the walking-beam is a pair of 10 U-shaped straps 30, that are located at opposite sides of the notch 11'. These straps serve to support a hanger-rod 31, that passes through the straps at the extreme forward end of the walking-beam and at the 15 lower corner of said end and upon which the loop of the temper-screw 27 is hung. By mounting the hanger supporting the temper-screw at the extreme forward end of the walking-beam and at the lower side of said 20 end I attain the advantage that when the walking-beam is tilted its entire travel is in a direction away from the tool-rope and therefore increases the clearance between the rope and the beam over what has heretofore been 25 obtainable in other mountings of the temper-screw.

The walking-beam of the machine is vibrated through the medium of a pitman 32, connected to its rear end and leading to a 30 crank 33, carried by a shaft 34. The shaft 34 is driven by a band-wheel 35.

36 is a friction-wheel mounted upon a shaft 37, that carries a rope-reel, and which is provided with an eccentric 38.

39 is a friction-wheel associated with the 35 band-wheel 35 and to which the friction-wheel 36 is adapted to be moved when the eccentric 38 is rocked through the medium of a throw-rod 40, having connection therewith and leading to a hand-lever 41.

40 I claim as my invention—

1. In a well-boring machine, the combination of a frame, a support associated with said frame, a tilting samson-post mounted upon said support, a walking-beam rockingly mounted on said samson-post, a jack-rod pivoted to said samson-post, a guiding-box, a slide-block reciprocally positioned in said guiding-box and to which said jack-rod is connected, a catch-plate mounted on said 45 frame, and a throw-rod connected to said slide-block and provided with a pin adapted to engage said catch-plate, substantially as set forth.

2. In a well-boring machine, the combination of a walking-beam, means whereby said walking-beam is rockingly supported, a temper-screw, and means for connecting said temper-screw to said walking-beam; said connecting means consisting of a pair of 50 straps fitted to the forward end of the walking-beam and a hanger-rod fitted within said straps at the lower forward extremity of said walking-beam, substantially as set forth.

55 LEROY K. ROBBINS.

In presence of—

BLANCHE HOGAN,
Wm. H. SCOTT.
